UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed October 20, 1919. Serial No. 331,856.

To all whom it may concern:

Be it known that I, ALFRED G. F. KUROWSKI, a citizen of the United States, formerly a citizen of Germany, residing in Brooklyn 5 Borough, in the county of Kings, city and State of New York, have invented certain new and useful Improvements in Type-writing Machines, of which the following is a specification.

10 This invention relates to typewriting machines, and more particularly to mechanism for effecting relative movement between the platen and the writing point of the machine, to enable the printing of characters 15 between the positions in which characters would be printed in the normal operation of the machine.

In typewriting, it is a common occurrence to omit one or more letters in the body of 20 a word, or to omit a letter at the end. In the first case, the error may be corrected by writing the letter in half-space position between two letters previously written, or by erasing the word and rewriting it, with 25 each of the letters displaced a half-space to the left in order to provide equal spaces between the rewritten word and the preceding and following words. In the second case, the letter to be added may be half- 30 spaced from the last letter of the word, so as to leave an interval between said letter and the following word. Other errors of the same nature may be corrected in the same general manner.

35 The principal object of this invention is to provide improved means for shifting the work a fraction of a letter-space with reference to the printing point, and for controlling the positioning of the work relatively to the printing point after such shifting has been effected.

In carrying out this invention, I may provide pivots to receive the hubs of the arms connected to the escapement rack, of such 45 length that the carriage may be moved longitudinally with respect to the rack. To control the position of the carriage relative to the rack, provision may be made of a pin on one of said hubs, engaging in a cam-slot 50 in a slide supported on the carriage. Means, including a finger-piece, may be provided for actuating said slide, and also a spring for returning said finger-piece. It will be seen that, by using slides having slots of 55 suitable inclination, mechanism of this kind

may be adapted for use with racks of different pitches.

Another feature resides in the provision in the margin-release lever of a slot into which the pivot-pin of the lever projects, 60 and of a spring normally pressing the margin-release lever against one side of the slide near its forward end. It will be seen that, upon actuating said slide, the margin-release lever will be moved by its spring across 65 the end of the slide and will maintain the same in actuated position. This feature is of particular value in case several corrections are to be made in the same line.

As a consequence of the use of the margin-release lever as a latch, another result is obtained, namely, the automatic withdrawal of the margin-release lever from its latching position, and the consequent release of the slide when the carriage is returned to 70 position to start a new line, due to the engagement of a lug on the margin-release lever with the right-hand margin-stop. By operating the machine in this manner, direct manual operation of the margin-release 75 lever to release the slide may be avoided.

Other features and advantages will hereinafter appear.

In the accompanying drawings,

Figure 1 is a fragmentary side elevation, 85 partly in section, showing my invention as applied to an Underwood typewriting machine.

Figure 2 is a perspective view of the slide shown in Figure 1.

Figure 3 is a fragmentary front elevation of a portion of the mechanism shown in Figure 1.

Figure 4 is a plan view of the parts at the right of Figure 3, shown as turned one-quarter around in clockwise direction.

Figure 5 is a view similar to Figure 3, but showing the parts in different positions.

Upon depression of the character-keys (not shown), type-bars 1 will be swung upwardly and rearwardly to bring the types thereon into engagement with the platen 2, supported by means of an axle 3, in a platen-frame 4, which, in turn, is supported in a typewriter carriage 5. Said carriage 5 is 100 mounted for movement transversely of the machine on front and rear rails 6 and 7, respectively, and is drawn towards the left 105 of the machine by means of the usual strap 8 and spring drum 9. Movement of said car- 110

riage 5, under the influence of the spring drum 9, is controlled by means of the usual escapement mechanism, comprising a rack 10, connected, by means of arms 11, with the carriage, and normally in engagement with a pinion 12, which has the usual one-way connection with an escapement wheel 12^a, the escapement wheel being controlled by the usual fast and loose dogs 13 and 14, respectively, mounted on a dog-rocker 15, supported on a pivot 16. When an operated type-bar is approaching the end of its stroke, a heel 17 thereon will engage the usual universal frame 18, and thereby effect actuation of the dog-rocker.

Provision is also made of a margin-stop 19, mounted for sliding movement on a rod 20 and on front rail 6, and held in position by engagement of a toothed jaw 21, forming part thereof, with teeth 22, formed on the front of rail 6. Said jaw 21 is pivoted to the margin-stop proper and may be withdrawn from teeth 22, by means of a finger-piece 23. When the carriage is returned to the position for starting a new line, a lug 24 on said margin-stop 19 will be engaged by a lug 25, carried by a margin-release-lever 26, the head 27 of which projects upwardly through a slot 28 in the front part of the carriage-frame.

In carrying out the present invention, it is desirable to provide means whereby a relative movement of the carriage 5 and rack 10 may be effected. To this end, shouldered screws 29, which carry the hubs 30 of said arms 11, are made of sufficient length to enable movement of hubs 30 therealong, the position of the carriage along the rack-member 10 being determined by means of a pin or cam follower 31 on one of said hubs 30, engaging in a cam-slot 32 in a lug 33, offset from a slide 34, forming a carriage-displacing member, which is slidably supported on the carriage by means of shouldered screws 35 engaging in slots 36. It will be seen that this arrangement does not interfere materially with the lifting of rack 10, by means of the usual carriage-release-lever 37. A spring 38, connected to the slide 34 at its rear end and to a pin on the carriage, tends to hold the slide in its forward position, which is determined by engagement of the rear ends of said slots 36 with the shouldered screws 35. When the slide 34 is in its forward or normal position, the carriage 5 will be held in its limiting right-hand position with reference to rack 10. When the slide 34 is moved to the rear, however, the carriage will be moved to the left with reference to the rack 10. It will be seen, in this connection, that rack 10 is held against movement to the left by means of the escapement mechanism, and that movement of said slide 34 to the rear allows the carriage proper to be drawn to the left by

means of the strap 8 and the spring drum 9.

For convenience in operating slide 34, a finger-piece 39 is pivotally mounted on the carriage-frame by means of a shouldered screw 40, and a screw 41, fixed in said finger-piece 39, engages in a slot 42 in the slide 34, said slot 42 being elongated vertically to allow for the upward movement of the screw 41 as the finger-piece 39 is swung about shouldered screw 40. It will be seen that unless return of slide 34 is prevented by some other means, the spring 38 will restore the slide and finger-piece to their normal positions.

It has been found desirable to provide latching means, for maintaining the slide in operated position, to enable corrections to be made without manually holding the finger-piece in operated position. To this end, the margin-release-lever 26 is provided with a slot 43, engaging the pivot of said lever, said pivot being here shown as a shouldered screw 44. Normally the margin-release-lever 26 is held with the right-hand end of slot 43 in engagement with screw 44, due to the engagement of the curved end 45 of the margin-release-lever 26 with the forward end 46 of the slide 34. It will be understood that the curved end of lever 26 is substantially in the shape of an arc of a circle, concentric with the arc at the right-hand end of slot 43, so that, with the parts in their Figure 3 positions, the margin-release-lever 26 may be actuated in the usual manner.

Upon movement of the slide 34 to the rear, however, the margin-release-lever 26 will be drawn to the right by means of a spring 47, and its head 27 will be positioned in front of the forward end 46 of slide 34, as shown in Figure 5, and will prevent the return of slide 34 by means of spring 38. If desired, the slide 34 may be released by pressing the head 27 of the margin-release-lever 26 to the left, to carry it from its Figure 5 position to its Figure 3 position. The slide 34 will then be returned to its normal position by spring 38, and the forward end 46 of said slide will maintain the margin-release-lever 26 in its Figure 3 position with reference to screw 44. It will be understood that movement of the margin-release-lever 26 to its Figure 5 position will displace lug 25 with reference to the typewriter carriage 5, so that said lug 25 will engage lug 24 of the margin-stop before the carriage has reached the end of its return movement, the result being that movement of the lever 26 will be stopped, and slide 34 will be carried sufficiently to the right thereof to free it from the head 27. The slide 34 will then be moved to its forward position by spring 38, and the forward end 46 of the slide will prevent movement of the margin-release-lever 26 by the spring 47. In other words, movement of the carriage to the position to start a

new line will effect automatic restoration of the parts to their normal positions.

In applying the invention to machines having racks of different pitches, it is necessary to supply slides having their cam-slots inclined in accordance with the rack in connection with which they are to be used. Obviously, this requirement may be met in other ways.

10 Variations may be resorted to within the scope of the invention, and portions of the improvements may be used without others.

Having thus described my invention, I claim:

15 1. In a typewriting machine, in combination, a traveling carriage, an escapement mechanism therefor including a rack, arms connected with said rack and having hubs at their free ends, pivots on said carriage 20 co-operating with said hubs and of sufficient length to enable movement of said carriage relatively to said rack, and means to shift said carriage, comprising a pin on one of said hubs and a slide on said carriage provided with a cam slot into which said pin projects.

2. In a typewriting machine, in combination, a traveling carriage having aligned pivots at opposite ends, escapement mechanism including a rack, arms fixed on said rack and provided with hubs to receive said pivots, said pivots being of sufficient length to permit movement of said hubs longitudinally thereof, means to move said carriage relatively to said rack, including a slide supported on the carriage, and a spring for restoring said slide to normal position.

3. In a typewriting machine, in combination, a traveling carriage, escapement mechanism including a rack, means, including a slide on said carriage, to shift said carriage relatively to said rack, means urging said slide in one direction, a margin-release-lever provided with a slot, a pin projecting into said slot, a spring urging said lever against the side of said slide near the forward end thereof, so that said release lever will move across the end of said slide upon movement of the slide to its actuated position, 45 a lug on said margin-release-lever, and a margin stop positioned so as to engage said lug when said carriage is moved to the right, and effect the withdrawal of said margin-release-lever from the end of said slide to 50 permit the return thereof.

4. In a typewriting machine, in combination, a traveling carriage, an escapement mechanism therefor including a rack, arms connected with said rack and having hubs 55 at their free ends, pivots on said carriage co-operating with said hubs and of sufficient length to enable movement of said carriage relatively to said rack, and means to shift said carriage comprising a movable cam member on said carriage, a spring nor-

mally holding said member in inactive position, means on one of said hubs engaging said cam member for shifting said carriage when the cam member is moved, and means for moving said member against the action of said spring.

5. In a typewriting machine, in combination, a traveling carriage, an escapement mechanism therefor including a rack, arms connected with said rack and having hubs at their free ends, pivots on said carriage co-operating with said hubs and of sufficient length to enable movement of said carriage relatively to said rack and laterally of the machine, and means to shift said carriage laterally comprising a cam member on said carriage movable forwardly and rearwardly, and normally in forward position, means on one of said hubs engaging said member for shifting said carriage when the cam member is moved rearwardly, and means for moving said member rearwardly.

6. In a typewriting machine, in combination, a traveling carriage, an escapement mechanism therefor including a rack, arms connected with said rack and having hubs at their free ends, pivots on said carriage co-operating with said hubs and of sufficient length to enable movement of said carriage relatively to said rack and laterally of the machine, and means to shift said carriage laterally comprising a cam member on said carriage movable forwardly and rearwardly, a spring normally holding said member in its forward position, means on one of said hubs engaging said member for shifting said carriage when the cam member is moved rearwardly, and means for moving said member rearwardly against the action of said spring.

7. In a typewriting machine, in combination, a traveling carriage, an escapement mechanism therefor including a rack, arms connected with said rack and having hubs at their free ends, pivots on said carriage co-operating with said hubs and of sufficient length to enable movement of said carriage relatively to said rack, means to shift said carriage comprising a movable cam member on said carriage, a spring normally holding said member in inactive position, means on one of said hubs engaging said cam member for shifting said carriage when the cam member is moved, and means for moving said member against the action of said spring, and a latch slidably mounted on said carriage and adapted to hold said member in moved position, said latch being movable to allow said member to return to inactive position.

8. In a typewriting machine, in combination, a traveling carriage, an escapement mechanism therefor including a rack, arms connected with said rack and having hubs at their free ends, pivots on said carriage

co-operating with said hubs and of sufficient length to enable movement of said carriage relatively to said rack, means to shift said carriage comprising a movable cam member on said carriage, a spring normally holding said member in inactive position, means on one of said hubs engaging said cam member for shifting said carriage when the cam member is moved, and means 10 for moving said member against the action of said spring, a latch slidably mounted on the carriage for movement laterally thereof, and a second spring normally pressing said latch in a direction to hold said member in moved position, said latch being movable against the action of said second spring to allow said member to return to inactive position.

9. In a typewriting machine, in combination, a traveling carriage, an escapement mechanism therefor including a rack, arms connected with said rack and having hubs at their free ends, pivots on said carriage co-operating with said hubs and of sufficient 20 length to enable movement of said carriage relatively to said rack and laterally of the machine, means to shift said carriage laterally comprising a cam member on said carriage movable forwardly and rearwardly, and normally in forward position, means on one of said hubs engaging said member for shifting said carriage when the cam member is moved rearwardly, and means for moving said member rearwardly, and a 25 latch slidably mounted on said carriage, said latch being adapted to engage in front of said member when the latter is moved rearwardly, said latch being movable to release said cam member and allow it to 30 return to its forward position.

10. In a typewriting machine, in combination, a traveling carriage, an escapement mechanism therefor including a rack, arms connected with said rack and having hubs 40 at their free ends, pivots on said carriage co-operating with said hubs and of sufficient length to enable movement of said carriage relatively to said rack and laterally of the machine, means to shift said carriage laterally comprising a cam member on said carriage movable forwardly and rearwardly, and normally in forward position, means on one of said hubs engaging said member for shifting said carriage when the cam member is moved rearwardly, and means 45 for moving said member rearwardly, a latch slidably mounted on said carriage, and a spring tending to move said latch in front of said member, said latch engaging in front of said member when the latter is moved rearwardly, said latch being movable against the action of said spring to release 50 said cam member and allow it to return to its forward position.

11. In a typewriting machine, in combi-

nation, a traveling carriage, an escapement mechanism therefor including a rack, arms connected with said rack and having hubs at their free ends, pivots on said carriage co-operating with said hubs and of sufficient length to enable movement of said carriage relatively to said rack and laterally of the machine, means to shift said carriage laterally comprising a cam member on said carriage movable forwardly and rearwardly, and normally in forward position, means on one of said hubs engaging said member for shifting said carriage when the cam member is moved rearwardly, and means for moving said member rearwardly, a margin-release-lever slidably mounted on said carriage, one end of said lever being adapted to engage in front of said member when the latter is moved rearwardly to hold the member in rearward position, and a margin-stop on the machine adapted to engage the other end of said lever when the carriage is retracted to its initial position to withdraw said latch and allow the cam member to return to its forward position.

12. In a typewriting machine, in combination, a traveling carriage, an escapement mechanism therefor including a rack, arms connected with said rack and having hubs at their free ends, pivots on said carriage co-operating with said hubs and of sufficient length to enable movement of said carriage relatively to said rack and laterally of the machine, means to shift said carriage laterally comprising a cam member on said carriage movable forwardly and rearwardly, and normally in forward position, means on one of said hubs engaging said member for shifting said carriage when the cam member is moved rearwardly, and means for moving said member rearwardly, a margin-release-lever slidably mounted on said carriage, one end of said lever being adapted to engage in front of said member when the latter is moved rearwardly to hold the member in rearward position, a spring tending to move said end to engage in front of said member, and a margin-stop on the machine adapted to engage the other end of said lever when the carriage is retracted to its initial position, said carriage being movable after said margin-stop has engaged said other end of the lever to move said cam member beyond said first end of the lever and out of engagement therewith to allow said member to return to its forward position.

13. In a typewriting machine, in combination, a main frame, a platen-carrying carriage to travel thereon, an escapement mechanism for said carriage including a rack-member having a movable connection with said carriage to permit longitudinal movement of said carriage independent of similar movement of said rack-member, a

- carriage-displacing member having a cam formed thereon and mounted on said carriage for backward and forward movement thereon, a restoring spring for said carriage-displacing member tending to maintain it at one of the limits of its movement, a cam-follower carried by said rack-member and having a movable connection with said cam for displacing said carriage along said rack-member by the movement of said carriage-displacing member against the tension of its restoring spring, a spring-pressed latch on said carriage automatically engageable with said carriage-displacing member to hold it against being returned by said restoring spring, and a latch-releasing lug on said main frame in the path of said latch to be engaged thereby to release said latch when said carriage is returned for beginning a new line.

14. In a typewriting machine, in combination, a main frame, a platen-carrying carriage to travel thereon, an escapement mechanism for said carriage including a rack-member having a movable connection with said carriage to permit longitudinal movement of said carriage independent of similar movement of said rack-member, a carriage-displacing slide-member mounted for a limited backward and forward sliding movement on said carriage, a restoring spring for said carriage-displacing slide-member tending to maintain it at one of its limits of movement, carriage-displacing connections between said carriage-displacing slide-member and said rack to be operated by moving said carriage-displacing slide-member against the tension of its restoring spring, a spring-pressed latch on said carriage automatically engageable directly with said carriage-displacing slide-member to hold it against being returned by said restoring spring, and a latch-releasing lug on said main frame in the path of said latch to engage and release said latch when said carriage is returned for beginning a new line.
